UNITED STATES PATENT OFFICE.

IRVING WILLIAM PECK, OF MACON, GEORGIA.

CUSHION-COVER FOR FRUIT-CRATES.

1,253,628.

Specification of Letters Patent. Patented Jan. 15, 1918.

Application filed September 20, 1915. Serial No. 51,707.

To all whom it may concern:

Be it known that I, IRVING W. PECK, a citizen of the United States, and a resident of Macon, in the county of Bibbs and State 5 of Georgia, have invented certain new and useful Improvements in Cushion-Covers for Fruit-Crates, of which the following is a specification.

My invention is an improvement in cushion covers for fruit crates, and the invention has for its object to provide a cushion of the character specified, for preventing injury to fruit during transportation, as for instance, peaches and the like, wherein a 15 particular type of cushion is provided connected to the under face of the cover, in such manner that the fruit is held tightly in the receptacle, yet yieldingly, to prevent injury to the same from movement in the 20 crate.

In the drawings:

Figure 1 is a perspective view from below of a cover provided with the improved cushion;

25 Fig. 2 is an enlarged partial longitudinal section of Fig. 1;

Fig. 3 is a transverse vertical section through the cushion.

The embodiment of the invention shown 30 in Figs. 1 and 2 is shown in connection with the cover of a crate, the said cover consisting of suitable boards 1, laid alongside each other, and connected by transverse strips 2 on one face, and by transverse bars 3 on 35 the other face.

The strips 2 are arranged at the center and at the ends of the cover, while the bars 3 are arranged at the ends. The cushion is composed of a sheet of paper or the like, 40 consisting of a body portion 4 which lies next the inner face of the cover, and side flanges 5, which are folded over on the body in spaced relation, as shown, and a filling 6 of cushioning material, as for instance 45 excelsior or the like arranged between the sides 5 and the body 4.

The sides 5 of the cushion overlap at their meeting edges as indicated at 7 in Figs. 1 and 3, and the cushion is of slightly 50 less area than the area of the cover.

As shown in Figs. 2 and 3, the cushion is of less length and of less width than the 55 crate cover, the cushion being of a size to fit between the end bars 3 outside of the crate.

In Fig. 2, the cushion 9 is shown attached

to the cover 10, by means of paper strips at the ends of the cushion. These strips have one side 11 pasted or otherwise secured to the inner face of the cover at the end, and 60 afterward the cushion is placed in such manner that its ends rest upon the pasted portions 11 of the strips.

The free sides 12 of the strips 11-12 are then folded over upon the ends of the cushion and the said portions 12 may be pasted or otherwise secured to the cushion if desired. The connecting portion 13 between the portions 11 and 12 of the strip closes the 65 ends of the cushion partially or completely, 70 thus holding the cushion firmly in place.

As shown in Figs. 2 and 3, the cushion is composed of a double thickness of material, the sheet 4-5 being arranged outside of a second sheet 14. This sheet 14 has its side 75 edges secured together as indicated at 15, to hold the excelsior in place, and the fold 15 is at a different place from the fold 7, to strengthen the cushion.

As is well known, in packing fruit, especially a delicate fruit like peaches, the fruit cannot be so arranged that the top will be exactly level, and in such manner that every portion of the top will contact with the same force with the fruit. There are irregularities, and with the usual form of rigid cover, some of the fruit is pressed too close, while other of it does not have sufficient pressure.

The crate as a rule must be packed too 80 tight or not tight enough, and either condition is equally undesirable. If the fruit is packed too tightly it will crush, while if it is packed too loosely, there will be movement and consequent bruising of the fruit. 85

With the cushion, however, these irregularities are compensated for, and there is a uniform pressure throughout the entire capacity of the crate. Unless the crates are handled in an exceptionally rough manner, 100 the fruit will not be injured.

I claim:

1. A cover for crates, flexible strips arranged at opposite edges of the cover and having edge portions attached thereto, and 105 a flat cushion placed against a side of the cover, and held in place by the said flexible strips, the loose edge portions of which overlap opposite parts of the cushion and are attached thereto.

2. A cover for crates, flexible strips arranged at opposite edges of the cover and

having edge portions attached thereto, and a flat cushion placed against a side of the cover, and held in place by the said flexible strips, the loose edge portions of which are folded around opposite edges of the cushion and secured thereto.

3. A cover for crates, flexible strips arranged at opposite edges of the cover and having edge portions attached thereto, and a flat cushion placed against a side of the cover with opposite edge portions overlapping the edge portions of the strips attached to the cover, and having the loose

edge portions of such strips folded over edge portions of the cushion and against the under side thereof to which they are attached.

4. A cover for crates, a flat cushion placed against a side of the cover and comprising a filling and a flexible retaining sheet, and strips closing the edges of the cushion and having edge portions attached to the cover and retaining sheets, respectively.

IRVING WILLIAM PECK.
